UNITED STATES PATENT OFFICE.

HARRY J. BREWER, OF NEW YORK, N. Y.

BUFFING-MACHINE.

No. 916,665.

Specification of Letters Patent. Patented March 30, 1909.

Application filed July 27, 1907. Serial No. 385,837.

To all whom it may concern:

Be it known that I, HARRY J. BREWER, a citizen of the United States, and a resident of New York, in the county of New York and State of New York, have invented a certain new and useful Improvement in Buffing-Machines, of which the following is a specification.

This invention relates to means for polishing or buffing round or tapering metal, or other parts, such as the plugs or jacks used in telegraphy and telephony, the object of the invention being to provide a durable and efficient device, simple and compact in construction.

The invention consists in features of construction and combinations of devices hereinafter described, and more particularly set forth in the appended claims.

20 One form of the invention is illustrated in the accompanying drawing, forming part hereof, in which—

Figure 1 is a side elevation; Fig. 2 is a front elevation of the carrier; and Fig. 3 is a 25 section of a modified form of holder.

In the drawing, the reference letter *a* designates an electric motor of any approved type or construction, and *b* denotes the rotary shaft thereof. Or other means for 30 driving the shaft *b* may be used. On the shaft *b*, a buffing, grinding, or polishing wheel *d* is made fast in any suitable manner, as by pinning its hub *e* to the shaft. The wheel *d* may be made of any construction or 35 material suitable to the purpose in view, or it may be coated, charged, or impregnated with any such substance.

Mounted on the shaft *b* to rotate independently thereof is a disk or carrier *e*, which 40 is held in place on the shaft in any suitable manner, as by a nut *f* on the shaft *b*. The carrier *e* preferably has a radial slot *g* therein to receive a tube *h*, and the tube *h* is locked in position by nuts *i* thereon, which engage 45 with threads on the outer surface thereof.

Or the nuts may be set up so that the tube may rotate in the slot. By means of the slot *g* and the nuts *i*, the tube *h* may be set at different distances from the axis of the carrier *e*, to correspond with buffing or other 50 wheels of different diameters. Or the tube *h* may be double, one tube being locked against rotation by the nuts *i* while the other, or inner, part may rotate therein; see *h*, *h*¹, Fig. 3.

In the use of the invention, the plug or jack *h* is thrust through the tube into contact with the periphery of the buffing wheel, and the carrier is then given one or more turns on its axis while the operator holds the 55 plug or jack from turning, whereby every part of the surface of the plug or jack is presented to the action of the rotating buffing wheel and receives a polish from the action thereof.

The above described device provides a simple and efficient means for polishing jacks and plugs, and may be readily carried about and be used to repolish jacks or plugs in central offices as well as in the works where such 60 are made.

What I claim as new and desire to secure by Letters Patent of the United States is—

1. In a buffing device, a buffing wheel and a carrier independently rotatable on the 65 same axis, and a jack or plug holder on the carrier.

2. In a buffing device, a buffing wheel and a carrier on the same axis but rotatable independently of each other, and a jack or plug holder on the carrier, with means for adjusting the position of the holder toward and from said axis.

Signed at New York city in the county of New York and State of New York this 29 80 day of March A. D. 1907.

HARRY J. BREWER.
